ELECTRIC SWITCH

Arvid H. Nero, West Hartford, Conn., assignor to
The Arrow-Hart & Hegeman Electric Company,
Hartford, Conn., a corporation of Connecticut

Application January 20, 1934, Serial No. 707,597

4 Claims. (Cl. 200—168)

This invention relates to electric switches or circuit breakers. More particularly it relates to an electric switch having a movable contact which is moved with a snap action into three different 5 positions for the control of circuit containing electric translating devices, such as electric heaters and electric stoves.

It is an object of this invention to provide a lever actuated snap switch for controlling heater 10 circuits, which switch has a movable contact capable of occupying two closed-circuit positions and an open-circuit position.

Another object is to provide a lever operated snap switch for heater circuits in which the 15 connections between the fixed contacts thereof may be varied easily to suit the different requirements of use to which the switch may be put.

Other objects and advantages of my invention will occur to those skilled in the art as the invention is described in connection with the accompanying drawings:—

In the drawings:—

Figure 1 is a plan view of the top half of a switch embodying my invention.

Figure 2 is a bottom view of the top half of the switch shown in Figure 1.

Figure 3 is a bottom view of the lower half of a switch embodying the principles of my invention.

Figure 4 is a broken sectional view taken longitudinally through the switch shown in Figures 1 and 2, the section being taken along lines 4—4 thereof.

Figure 5 is a transverse sectional view of the switch shown in the preceding figures, the section being taken along line 5—5 of Figure 2.

Referring to the drawings the switch embodies a base comprising an upper half 10 and a lower half 12 which are generally in the form of 40 octagonal prisms. The top half 10 of the base has formed in its upper surface 4 identical irregularly shaped curved channels 14, 16, 18 and 20, these channels connecting countersunk bores 22 and 24, 26 and 28, 30 and 32, 34 and 36 respectively, the bores 22, 26, 30 and 34 being located at one end of the base while the bores 24, 28, 32 and 36 are located at the other end of the base. Each bore penetrates the base from one side to the other. The bores 30 and 34 are positioned symmetrically, at one side of the center line of the base with respect to the bores 22 and 26 which are at the other side. Similarly the bores 32 and 36 are positioned symmetrically with respect to the bores 24 and 28. In each of 50 the bores there is a mounting screw which takes

into a square nut at the other side of the upper half of the base underneath which nut is seated a fixed contact member which is of L shape. For illustration of this construction reference may be had to the mounting screw 23 which is 5 contained in the bore 22 and takes into nut 42 to hold the contact 54 in position.

That portion of the contact 54 which is adapted to be engaged by a movable contact (hereinafter described) may be seen at 54s. It is in alignment with similar contact engaging surfaces 52s, 56s and 58s, all of these contact surfaces being on one side of the center line of the switch base but the surfaces 52s and 54s are at the opposite end of the base from the surfaces 56s and 58s. 10 Similarly on the other side of the center line of the base are aligned contact surfaces 44s, 46s, 48s and 50s. Preferably the stationary contacts and nuts are seated within rectangular recesses (see for example the recess 43 for the contact 54). 20

It will now be apparent that the contact 46 may be connected with the contact 48 by a bus bar 49 which may be seated in the channel 20 and secured therein by the same screws 35 and 37 which mount the switch contacts in their 25 recesses in the opposite face of the base. Similarly contacts 52 and 56 are connected by a bus bar 53 and contacts 54 and 58 are connected by a bus bar 55. In the switch shown no bus bar is placed in the channel 18 and therefore the 30 contacts 44 and 50 are not connected together. The channels 14, 16, 18 and 20, being identical, it is possible to use the bus bars 49, 53, 55, interchangeably or to omit or add one as dictated by the requirements of the different circuits in which 35 the switch is to be used.

In order to bridge the contacts 44 and 46 and at the same time bridge contacts 52 and 54, bridging members 60 and 62 are mounted upon the end of a switch member 64 which may be 40 movable with a snap action by a hand lever 66 by means of any suitable snap switch mechanism, for example that shown in the patent to Monroe Guett 1,878,843 patented September 20, 1932. Since this snap mechanism is now well known it 45 is unnecessary to describe or illustrate it herein. It should be noted, however, that the switch mechanism shown in this patent is capable of moving the switch member into three working positions, the two extreme positions being the 50 circuit making positions and the intermediate position being an open circuit position. In the present invention, the switch is in open circuit position in Figures 1, 2 and 5 and is in one closed circuit position in Figure 4. 55

The bridging members 60 and 62 are mounted upon the end of the switching member 64 by means of pins 68 passing transversely through the end portion of the switching member 64 and having insulating collars 70 and 72 thereon on opposite sides of the switching member. The movable contacts 60 and 62 are secured against the outer ends of the insulating collars by the bending over the ends of the transverse pins 68, an insulating washer 74 being provided to insulate the pins 68 from the contacts. Thus the contacts are mutually insulated from one another and from the switching member 64.

Referring to Figures 2 and 4 it will be noted that each movable contact or bridging member is made of two laminations of thin sheet metal which are stamped into approximately H shape. The ends of the laminations are bent outwardly to facilitate the engagement thereof with the contact surfaces of the fixed contacts, according to well known switch practice. Preferably the contact arms of the movable contact are arcuate, the inner ones being shorter than the outer ones in order that when they engage with the fixed contacts, the inner and outer arms will engage with the inner and outer contacts, respectively, at the same instant.

It will now be observed that when the switch is in position shown in Figure 4 stationary contacts 48 and 50 will be bridged by the movable contact 60 and contacts 56 and 58 will be bridged by the movable contact 62. When the switch is in the positions shown in Figures 1, 2 and 5, no stationary contact will be engaged by a movable contact. When the switch is in the opposite extreme position from that shown in Figure 4 the stationary contacts 44 and 46 will be bridged by the movable contact 60 and the stationary contacts 52 and 54 will be bridged by the movable contact 62.

It is desirable to have the stationary and movable contacts completely enclosed in order that the moisture and dirt may be prevented from collecting upon them. Therefore I have provided 45 a lower half 12 for the switch casing. This portion of the casing has a central arcuate recess 80 in its upper or inner face, to permit free movement of the movable contact members.

In order that feed wires may be connected with 50 the stationary contacts wire terminals are provided upon the bottom surfaces of the lower half of the switch casing, these terminals being connected with the stationary contacts by long screws or bolts passing through the lower half 12 55 of the casing and taking into the square nuts (see for example nut 41 which with its screw 40 holds in place the fixed contact 44). The screw 82 which takes into nut 41, and the similar screws which take into the other contacts, not only serve 60 to connect the wire terminals with the fixed contacts but also serve to hold the upper and lower parts of the base together.

The wire terminals may consist of a washer 81 with a tab or extension 83 which is engaged 65 by the long screws for example, the long screw 82. The binding screws 84 may be threaded into the washers in order that the feed wire may be turned around and secured thereto according to common practice.

In case it is desired to mount the switch directly upon the bus bars of an electric range, angled extensions or conductors 86, 88, 90 may be provided and may be secured to the washers by screws 87, 89, 91 respectively taking the place 5 of the binding screws 84.

This switch is capable of and is particularly adapted to use in the circuit shown in my co-pending application filed coincidentally herewith, entitled "Heater circuit", Serial Number 707,598. 10

A face plate or cover for the switch is provided as at 96. This may be of any convenient design. A sheet of insulation such as fibre, may be provided between the face plate and the base, to insulate the contact holding screws 23, 30, 35, 37 15 etc. from the face plate.

Many modifications within the scope of my invention will occur to those skilled in the art. Therefore I do not limit the invention to the specific form illustrated. 20

I claim:—

1. An electric switch comprising cooperating base parts of insulating material, fixed and movable switch contacts and mechanism for moving the movable contacts with a snap action on one 25 of said base parts, internally threaded members and screws engaged therewith for holding said fixed contacts to said one base part, wire terminals and bolts on the other base part, said bolts engaging with said threaded members and wire 30 terminals and holding said base parts together.

2. An electric switch comprising cooperating base parts of insulating material, fixed and movable switch contacts and mechanism for moving the movable contact with a snap motion on one 35 of said base parts, wire terminals on the other of said base parts, and means securing said terminals to their base part and securing said base parts immovably together and electrically connecting said terminals to said contacts. 40

3. An electric switch comprising cooperating base parts of insulating material, fixed and movable switch contacts and mechanism for moving the movable contact with a snap motion on one 45 of said base parts, wire terminals on the back face of the other of said parts, and means securing said terminals against said back face and securing said base parts immovably together and electrically connecting said terminals to said contacts.

4. An electric switch comprising cooperating base parts of insulating material, groups of switch contacts at opposite ends of one of said base parts, a movable switch member adapted to engage with one or the other or neither of said 55 groups of stationary contacts at will, an oscillatory operating lever extending from the face of said base opposite to that upon which the switch contacts are, and mechanism for moving said movable contact with a snap into or from any 60 one of its three positions, and rigid interchangeable conductors seated in unconnected channels in one face of said base and connecting certain of said fixed contacts, wire terminals on the other of said base parts, and conducting means securing 65 said base parts together and connecting said wire terminals to said switch contacts.

ARVID H. NERO.
